UNITED STATES PATENT OFFICE.

GEORGE W. GOLAY, OF MIDDLE GROVE, MISSOURI.

DEVICE FOR INCREASING THE THROW OF CONNECTING-RODS.

SPECIFICATION forming part of Letters Patent No. 250,523, dated December 6, 1881.

Application filed September 30, 1881. (No model.)

To all whom it may concern:

Be it known that I, GEORGE W. GOLAY, of Middle Grove, in the county of Monroe and State of Missouri, have invented a new and useful Improvement in Devices for Increasing the Throw of the Connecting-Rod of Reciprocating Engines; and I do hereby declare that the following is a full, clear, and exact description of the same, reference being had to the accompanying drawings, forming part of this specification, in which—

Figure 1 is a side elevation. Fig. 2 is a longitudinal section on line $x x$, Fig. 1.

My invention relates to improvements in devices for increasing or lengthening the throw of the connecting-rod of reciprocating engines; and it consists in the peculiar construction and arrangement of the parts, as hereinafter more fully set forth.

20 In the accompanying drawings, a represents a plate provided with upturned ends b and projecting pieces c , having holes for the passage of bolts, by means of which the plate may be secured to a suitable frame in a vertical position.

$d d'$ represent two parallel horizontal bars, secured to the upturned ends of the plate a by screw-bolts and nuts, with a space or opening between the bars and between the latter and the outer face of the plate a . The upper bar, d , is provided with upwardly-projecting slotted ends, through which screw-bolts provided with nuts pass, whereby the upper bar, d , can be adjusted vertically.

35 h represents a bar lying against the bar d' , and provided with a wrist-pin, i , at its forward end, to which the outer end of the piston-rod k of a reciprocating engine may be secured.

l represents a keeper passing around the bars $h d'$, and retaining them in contact with each other, and at the same time allowing the bar h to slide back and forth on the bar d' .

To the enlarged rear end of the bar h the arms $m m$, lying on opposite sides of the bar h , 45 are pivotally secured, and the outer ends of the arms $m m$ are pivoted in the enlarged outer

ends, n , of arms o , the inner ends of the arms o being pivoted in one of the projecting pieces c , forming part of the back plate, a .

To the enlarged outer ends, n , of the arms o are also pivotally secured the arms p , the inner ends of the latter being pivoted to the enlarged outer end of a bar, q , resting against the bar d' and adapted to slide thereon, and held in contact therewith by the keepers $r r$, 55 passing around the bars $q d'$.

The arms $m m$ are of the same length and form and lie on opposite sides of the bar h . The arms $o o$ are also of the same length and shape, and lie on opposite sides of the bar h , 60 and also the arms $p p$.

To the bar q , near its inner end, is secured a wrist-pin, s , to which the inner end of the connecting-rod t is secured, the outer end of the connecting-rod being secured to the outer end 65 of a crank, u , on the shaft v .

The sliding bars q , with their pivoted arms and the plate a , are arranged in a vertical plane.

In the ordinary construction in reciprocating engines the inner end of the connecting-rod is pivotally secured to the cross-head at the outer end of the piston-rod, whereas in my construction the wrist-pin s of the bar q has a much longer stroke or reciprocation than the wrist-pin i of the bar h , whereby the throw of 70 the connecting-rod is much lengthened or increased, enabling the employment of a longer crank-arm and a consequent increase of speed. The length of throw of the connecting-rod can be varied as desired by varying the lengths 75 of the pivoted arms.

I claim as my invention—

In a reciprocating engine, the combination, with the plate a , bars $d d'$, sliding bar h , and pivoted arms $m m o o$, of the sliding bar q and 85 pivoted arms $p p$, whereby the throw of the connecting-rod is increased or lengthened, substantially as described.

GEORGE W. GOLAY.
